(57) **CLAIM**

The ornamental design for a drain grate, as shown and described.

DESCRIPTION

FIG. 1 is a perspective view of a drain grate embodying my new design;

FIG. 2 is a top view thereof;

FIG. 3 is a side view thereof, the opposing side view being a mirror image thereof; and,

FIG. 4 is a side view thereof, the opposing side view being a mirror image thereof.

The broken lines shown in the figures depict portions of the drain grate that form no part of the claim.
